HEEL PATCH FOR LOCOMOTIVE SIPHONS

Edward Henry Heidel, Milwaukee, Wis.

Application September 23, 1940, Serial No. 357,894

2 Claims. (CL. 122—68)

In steam locomotives a considerable increase of steam-generating efficiency has been accomplished in recent years by the provision of a special type of water heating tube called a siphon. The siphon is a large flat conduit or water leg extending through the space formed by the firebox and combustion chamber of a locomotive boiler from the throat at the bottom of the main portion of the boiler to the top of the boiler. Water flows in through a narrow tubular-shaped neck at the bottom, and, as it is heated and progressively transformed to steam, it rises rapidly in the siphon and ensures rapid circulation of the water in the boiler with consequent increased efficiency.

It has long been known that these siphons burn and deteriorate relatively fast at the top of the siphon, particularly along the back edge thereof against which the combustion products impinge. Possibly heated particles carried by the gases of combustion strike this back edge at this point and have an abrasive effect. It has been the custom for a number of years to apply a patch at this point, called the heel of the siphon, before it burned thin enough to be dangerous. Because of the complicated shape of the siphon at this point, these patches have been made of two parts welded together. In applying the patch a portion of the original siphon has been cut away and the patch welded in its place. The two parts of the patch were welded together approximately along a center line which extended along the back edge of the siphon. Applicant has determined that this practice is undesirable for two reasons. First, the patch with two parts welded together is relatively expensive; and second the metal of the weld is less resistant to burning or deterioration under the conditions of service than the original metal, and this tends to shorten the life of the patch.

According to the present invention a one-piece patch is provided in spite of the complicated shape which has heretofore been deemed to require a two-part patch. Instead of the life of the patch being shortened by welding or by the distortions resulting from its complicated shape, its life is, surprisingly, lengthened. When the particular shape required is formed by the method of this invention, the patch is thickened in the zone of greatest deterioration, and the metal in this thickened zone can have the same desirable characteristics as the rest of the metal in the patch or in the siphon.

Additional objects and advantages of the in-

vention will be apparent from the following description and from the drawings, in which:

Fig. 1 is a somewhat diagrammatic sectional fragmentary view of a locomotive boiler showing two siphons having thereon the heel patches of this invention.

Fig. 2 is a fragmentary sectional view taken approximately on the line 2—2 of Fig. 1 to show a transverse cross section of the siphon. In both Figs. 1 and 2 the staybolts for the main portion of the boiler are omitted.

Fig. 3 is a longitudinal sectional view through a heel patch of this invention.

Fig. 4 is a perspective view of the heel patch shown in Fig. 3.

Fig. 5 is a plan view of the blank from which the heel patch is made.

Fig. 6 is an exploded view showing the first top forming block and showing removed therefrom the blank of Fig. 5 as it has been reshaped during the use of said block.

Fig. 7 is a corresponding view showing the second top block and the blank of Fig. 6 as it has been reshaped thereby.

Fig. 8 is a similar view showing the final top block, the final shape of the blank, and the bottom forming block which is used with all three top blocks.

A preferred form of the invention has been chosen for illustration and description, in compliance with section 4888 of the Revised Statutes, but persons skilled in the art will readily perceive other means for accomplishing the same results, and the claims are therefore to be construed as broadly as possible, consistent with the prior art.

Fig. 1 shows in vertical section the rear portion of a boiler 11 having siphons therein, each of the siphons having a patch made in accordance with the present invention. Conventional parts of the boiler include the firedoor hole 12 through which coal is inserted by the fireman. The portion 13 of the boiler from the door 12 forwardly to the front end of the throat 14 is called the firebox (the grate not being shown), and the portion 16 from the throat 14 to the diagrammatically illustrated back tube sheet 17 is known as the combustion chamber. The flames and hot gases resulting therefrom flow from the firebox 13 through the combustion chamber 16 and forwardly through tubes or flues beginning at the tube sheet 17 and extending forwardly to the front end of the boiler. The tubes and all of the internal walls of the boiler are in contact with

water and hence transfer the heat from the fire to the water to generate steam.

To a large extent the steam-generating efficiency of a boiler depends upon the area of heating surface exposed to the hot gases. It has been common to increase the amount of heating surface by adding thermic siphons 18 and 19, as described, for example, on pages 298 to 301 of "Locomotive Cyclopedic," 1938. Water flows from the throat 14 through a tubular neck 21 of the siphon into the main body of the siphon. Because a small body of water in the siphon is heated from both sides, it is heated very rapidly. The flow of water through the siphon due to convection is therefore quite rapid and results in an increased circulation of water throughout the boiler. Normally a fairly large amount of the water will be transformed into steam as it rises through the siphon and the steam will have the effect of still further increasing the circulation.

In Fig. 1 patches 23, 24 and 25 have been shown on the siphons 18 and 19. The chief deterioration of the main portions of the siphons occurs in the zone indicated by the arrows 26, namely near the top of each siphon and at the rear center line thereof. Accordingly, the patches 23 and 25 are the ones most commonly used but sometimes a patch is required at the front side of siphon 19, as at the position of the patch 24. The sweep of the flames along the central and lower parts of the siphons is obstructed by arches 27.

The patch made in accordance with this invention is shown best in Fig. 4 with the cross section thereof seen in Fig. 3. These patches correspond very closely in general shape to the portion of the siphon which they replace. In applying them, the defective portion of the siphon is cut away and the patch is applied in its place by autogenous butt welding.

It will be observed from Figs. 3 and 4 that the patches are of a very complex shape to be formed by reshaping a flat piece of metal. The difficulty of reforming the plate cannot fully be appreciated from visualizing the drawings alone because it is difficult to realize the size of the parts involved and hence the depth of draw required. This can better be realized by noting that the blank 28 shown in Fig. 5 measures over 3 feet across from tip to tip.

The method of forming the patch is shown in Figs. 5 to 8. The blank 28 is drawn approximately to scale, and according to one manufacturer's process is made of $\frac{3}{8}$ inch stock. The blank 28, suitably heated, is positioned over the bottom block or forming die 31, and the first top block 32 is dropped thereon to shape the blank 28 to the first intermediate stage shown at 28a. It will be observed that along the longitudinal center line 33 the blank has assumed approximately its final shape, the top block 32 being complementary along this line to the bottom block 31. Next, the second top block 34 is dropped on the intermediate blank 28a, which may have been reheated if necessary, and the blank is shaped by it to the second intermediate stage 28b. Finally, the final top block 36 is dropped on the blank 28b, which is still (or again after reheating) positioned on the bottom block 31. The top block 36 is complementary to the bottom block 31 with the blank or unfinished patch 28c thereon, and hence this is the final step of the reshaping process. Subsequently, the patch is trimmed to the outlines desired and provided with the necessary staybolt holes 38 for staybolts

extending through the patch and the holes 33 for rivets for securing the patch to the crown sheets of the boiler or for staybolts if the latter are used in place of rivets.

By reshaping the block through the plurality of stages illustrated, excessive crimping of the blank is avoided and a very important independent result is accomplished. This is a thickening of the wall of the patch in the zone of the arrows 26-26 where the greatest deterioration occurs in use. It is not necessary, of course, to explain just how this thickening occurs, but it is obvious that in the course of the reshaping treatment described some parts must stretch and other parts must contract. The provision of the multi-stage reshaping described results in a contraction in the proper places to provide the thickening in the zone 26-26. Measurements have shown this thickening to amount to approximately $\frac{1}{8}$ of an inch in the case of a $\frac{3}{8}$ inch blank. Although even a thickening of $\frac{1}{8}$ the original thickness would obviously be important, the results are even more important than this because of course the siphon may not be allowed to burn through. If we assume, for example, that the siphon or the patch must be replaced when it is burned down to a thickness of $\frac{1}{4}$ of an inch, the increase in thickness from an initial $\frac{3}{8}$ inch to an initial $\frac{1}{2}$ inch thickness doubles the thickness of metal in excess of the minimum and hence tends to double the length of time before the thickness reaches the minimum safe thickness.

As will be apparent from Figs. 5-8, the metal in the upper portion of Fig. 5 forms the base portion of the flange, i. e. that portion of the flange forming the base of the U formed by the flange and through which the hole 39 in Fig. 3 is drilled. This portion of the metal is not altered and hence retains its original thickness. As a matter of fact, the molds shown in Figs. 6, 7 and 8, act to more or less gather the metal in from the Fig. 5 shape to the Fig. 8 shape, pushing the sides inwardly so that there is very little reduction in thickness of the metal at any point, this being an inherent advantage of the molding steps shown.

Heretofore patches similar in general outline to the patch of Figs. 3 and 4 have been provided by welding two half portions along the center line. Instead of providing a thickened portion of the plate itself at the zone of most rapid deterioration, this method left a weld at this position and it has been found that the weld deteriorated more rapidly than the metal of the plate, which may be ordinary boiler plate stock. In short, instead of providing at the point of greatest deterioration a surface weakened or softened by welding, I provide a section of metal which was initially of at least full strength and toughness but has been greatly increased in durability by a very substantial thickening.

I claim:

1. A heel patch for a locomotive siphon, comprising a single plate of metal shaped to form the U-shaped heel of the siphon and a securing flange extending outwardly from an edge thereof along the legs and base of the U and connected thereto with a curved portion, the outer part of the flange being in the form of an integral generally flat U lying in a plane approximately perpendicular to the plane of a wall of the siphon, the entire flange being at least as thick, approximately, as the thinnest portion of the remainder of the patch, and the patch be-

ing thickened along that part of the common center lines of the U bases lying in the connecting curve between the heel and the flange.

2. A heel patch for a locomotive siphon, comprising a single piece of metal having the grain structure and variation of thickness resulting from having been drawn and shaped from a blank comprising a flat metal plate to form the U-shaped heel of the siphon and with a securing flange extending outwardly from an edge thereof along the legs and base of the U and connected thereto with a curved portion, the outer

part of the flange being in the form of an integral generally flat U lying in a plane approximately perpendicular to the plane of a wall of the siphon, the flange throughout the base of said flat U being approximately as thick as the original plate from which the patch is shaped, and the patch being thickened along that part of the common center lines of the U bases lying in the connecting curve between the heel and the flange.

EDWARD HENRY HEIDEL.
